ATTORNEY

UNITED STATES PATENT OFFICE.

ROLLA CUMMINGS, OF TEEDEE, MONTANA.

GATE-FASTENER.

1,261,365.

Specification of Letters Patent. Patented Apr. 2, 1918.

Application filed October 8, 1917. Serial No. 195,395.

To all whom it may concern:

Be it known that I, ROLLA CUMMINGS, a citizen of the United States, residing at Teedee, in the county of Custer and State 5 of Montana, have invented certain new and useful Improvements in Gate-Fasteners, of which the following is a specification.

This invention relates to gates and more particularly to certain new and useful improvements in gate latches or fastening means.

The primary object of this invention is to provide an improved gate latch especially intended to be used in connection with wire 15 gates of the type commonly constructed by farmers as part of a cattle inclosure and which is adapted to hold taut the wire strands of the gate, whereby to prevent the usual sagging or slacking which allows the 20 cattle to escape.

A further object of the invention is to provide a latch of the above general character, which comprehends the employment of a locking lever adapted to be attached 25 to one of the gate posts and a loop or ring adapted to be engaged with the gate, means being provided for flexibly and adjustably connecting the loop with the lever whereby to regulate the pulling strain exerted on the 30 gate and to permit adjustment for use with gates of varying sizes.

The above and other objects as well as the construction and operation of the invention will be more readily understood from the 35 following description and drawings, in which drawings:—

Figure 1 is a top plan view of the invention in applied position.

Fig. 2 is a side view, and

Fig. 3 is a view showing certain details of construction.

In the drawings the numeral 1 is used to designate a fence post having the upper end thereof cut away to provide a flat face 2. Secured against the face 2 is a flat plate 3 which is fastened in position by means of a bolt 4 passing therethrough and the post 1. The plate 3 is provided in any suitable manner with a pair of vertical spaced ribs 5 which are on the side adjacent the post and are adapted to be embedded therein to more securely retain the plate in position. Hingedly connected to the lower edge of the plate 3, as at 6 is a flat semi-circular plate 7 which in operative position, is adapted to extend outwardly at right angles to the plate

3. This plate 7 has the opposite sides thereof provided with notches 8 positioned in proximity to the hinged connection 6, and at a point intermediate these notches and in 60 a direct line therewith is further provided with an opening through which extends a bolt 9, to which is pivotally connected one end of an arm 10. This arm 10 is arranged beneath the plate and is movable to either 65 side thereof. The free or outer end of the arm is slotted as at 11 and positioned on opposite sides of this slot is a pair of up-standing ears 12 which have their inner vertical edges recessed as at 13 to receive the 70 curved peripheral edge of the plate 7.

Pivotal secured between the ears 12 by means of a pivot bolt 14 is the enlarged head 15 of a handle lever 16 which handle lever is adapted to be moved to either side of the 75 semi-circular plate and received in one of the notches 8.

Pivotal connected to the arm 10 as indicated at 17 is one end of a coupling member 18 the opposite end of which is bifurcated 80 and provided on opposite sides of the bifurcation with depending lugs 19 apertured as at 20. A chain 21 has one of the links thereof positioned in the bifurcated end of the member 18 and secured between the lugs 85 19 by means of a cotter pin 22 passing therethrough. To an end of this chain is attached a loop or ring 23 which is adapted to be engaged with an upright 24 of the wire gate.

In Fig. 1 the latch is shown in a gate locking position, but in a normal or released position the arm 10 is adapted to extend outwardly at right angles to the plate 3 being thus positioned at a point directly 95 between the notches 8. The ring or loop 23 is then engaged with the portion 24 of the gate and the lever 16 is then operated to move the arm 10 to the position shown in Fig. 1 thus drawing the chain 21 and loop 100 23 in the direction of the post 1, holding the gate shut and properly stretching the wire strands thereof. When the arm 10 is in the position shown in Fig. 1 the lever 16 is received in one of the notches 8 to prevent 105 any accidental release of the latch and the notch into which the lever is placed depends on the side to which the arm 10 is moved. To open the gate the lever 10 is first disengaged from the notch and the 110 arm 10 is swung to a position intermediate the two notches thus loosening the chain 21.

and allowing the loop 23 to be readily disengaged with the gate. The strain exerted on the gate can be adjusted by engaging different links of the chain between the 5 lugs 19 of the coupling member 18.

When the arm 10 has been moved to a releasing position at right angles to the post 1 and the loop 22 is disengaged with the gate the plate 7 is adapted to swing 10 downwardly to lie against the flat face 2 below the plate 3 whereby to permit the lever from being sprung by the cattle rubbing against the same.

From the foregoing it is thought that the 15 operation and construction of this invention is clear and I wish to state herein that I reserve the right to make all desired changes that come within the scope of the appended claims and do not depart from the spirit 20 of the invention.

I claim:

1. A gate fastener including a semi-circular plate having notches formed in the periphery thereof a movable arm secured 25 to said plate, a lever attached to the free end of said arm and adapted to be received in said notches, a coupling member secured to said arm, a chain adjustably fastened to said coupling member, and a ring carried 30 by said chain.

2. A gate fastener, comprising a plate adapted to be fastened to a fence post, a second plate hingedly connected to said first mentioned plate and having notches formed 35 in the periphery thereof, an arm pivotally connected to said plate, ears formed on the free end of said arm and recessed to receive the curved edge of said plate, an operating lever pivotally secured between said 40 ears and adapted to be received in said notches, a chain adjustably secured to said arm, and a ring carried by said chain.

3. A gate fastener, including a plate adapted to be fastened to a fence post and

having vertical ribs formed on the inner 45 face thereof, a second semi-circular plate hingedly secured to the lower edge of said first mentioned plate and provided with notches in its periphery, an arm having one end pivotally connected to said semi-circular plate, the free end of said arm being cut to provide a slot, upstanding ears positioned on either side of said slot and recessed to receive the edge of the semi-circular plate, a lever pivotally secured between 50 said ears and adapted to be received in said notches, a coupling member movably secured to said arm intermediate the ends thereof, a chain secured to said coupling member, and a ring carried by said chain. 55

4. A gate fastener, including a plate, an arm pivoted to said plate and arranged to swing in the arc of a circle said arm having a slot formed in the free end thereof, an actuating lever pivoted in said slot and engageable with the plate to lock the arm against swinging movement, and a fastening ring carried by said arm. 60

5. A gate fastener, including a plate, an arm having one end pivoted thereto, a lever 70 directly pivoted to the free end of said arm and adapted for locking engagement with said plate, a coupling member secured to the intermediate portion of said arm and having a slot formed therein, ears extending 75 from said coupling member on opposite sides of said slot, a chain having one of its links arranged in said slot between said ears, and a fastening pin passing through said ears and link and a ring carried by said 80 chain.

In testimony whereof I affix my signature in presence of two witnesses.

ROLLA CUMMINGS.
